UNITED STATES PATENT OFFICE.

WILLIAM W. WHITE, OF NEW YORK, N. Y.

CALENDAR.

1,343,601.

Specification of Letters Patent. Patented June 15, 1920.

Application filed July 31, 1918. Serial No. 247,528.

To all whom it may concern:

Be it known that I, WILLIAM W. WHITE, a citizen of the United States, and resident of the borough of Manhattan, in the city and 5 State of New York, have invented a new and useful Improvement in Calendars, of which the following is a specification.

One object of my invention is to provide removable and reversible indicating tabs 10 having hinged tongues for insertion in grooves along a calendar board, the tongues being shaped to frictionally engage the side walls of the grooves to prevent their unintentional removal.

Another object is to make the tabs of 15 such a length that their free ends will snap over the hinges of adjoining tabs for holding the tabs snugly against the face of the board.

Another object is to provide each number 20 indicating tab with the number on one side distinguished from the same number on the other side so that the Sundays and other holidays in any month may be indicated by reversing the required tabs.

Another object is to provide a very inexpensive and attractive calendar which will be useful for a period of years.

A practical embodiment of my invention 25 is represented in the accompanying drawings, in which—

Figure 1 is a front view of my improved calendar,

Fig. 2 is a detail back view of the same,

Fig. 3 is a considerably enlarged detail section taken in the plane of the line III—III of Fig. 1,

Fig. 4 is a detail front view of one of the numeral indicating pads,

Fig. 5 is a section taken in the plane of the line V—V of Fig. 4,

Fig. 6 is a back view of the numeral indicating tab,

Fig. 7 is a section taken in the plane of the line VII—VII of Fig. 6,

Fig. 8 is a front view of a month indicating tab,

Fig. 9 is a detail back view of the same,

Fig. 10 is a front view of a year indicating tab, and

Fig. 11 is a back view of the same.

The front face of the calendar board 1 is provided with a number of transversely arranged parallel grooves, the groove 2 be-

ing intended to receive the tongues 3 and 4 55 of the year and month tabs 5 and 6, respectively, and the grooves 7 being intended to receive the tongues 8 of the numeral indicating tabs 9. The back face of the calendar board 1 is provided with a plurality of 60 transverse parallel grooves, the grooves 10 being intended to receive the tongues of the spare year and month tabs and the groove 11 being intended to receive the tongues of the spare numeral indicating tabs. 65

The front face of the calendar board 1 bears the days of the week arranged transversely across the same, in the present instance by providing a strip 12 of metal or other suitable sheet material secured to the 70 board.

All of the tabs are reversible, the opposite faces of the year indicating tabs bearing numbers of different years and the opposite faces of the month indicating tabs bearing 75 different months so as to reduce the number of tabs to a minimum.

The number on one side of each of the number indicating tabs is distinguished from the same number on the other side of 80 the said tab, as, for instance, by printing the numbers in different colors so that the Sundays and other holidays in any one month may be indicated by reversing the required number indicating tab. 85

The tongues on all of the tabs are so shaped that they will frictionally engage the side walls of the grooves when inserted therein to hold the tabs against unintentional removal. This may be accomplished 90 by bending the tongues as indicated at 13.

The number indicating tabs are sufficiently long so that when placed in position their free ends will have to be snapped over the hinges 14 of adjoining tabs. This will cause 95 the tabs to be held snugly against the face of the calendar board.

It is intended that the tabs shall be made of thin sheet material, such, for instance, as sheet metal.

If so desired, blank tabs may be provided for the blank spaces left by the rearrangement of the number indicating tabs for different months and by the removal of the later numbers for months of a lesser number 105 of days.

What I claim is:—

1. A calendar comprising a board having

parallel grooves along its face and reversible indicating tabs having hinged tongues fitted to be inserted in said grooves.

2. A calendar comprising a board having parallel grooves along its face and reversible indicating tabs having hinged tongues shaped to frictionally engage the walls of the grooves when inserted therein, to prevent the unintentional removal of the tabs.

10 3. A calendar comprising a board having parallel grooves along its face and reversible indicating tabs having hinged tongues fitted to be inserted in said grooves, the tabs being of such length that their free ends will snap

over the hinges of adjoining tabs to hold 15 the tabs snugly against the board.

4. A calendar comprising a board having parallel grooves along its front and back faces and reversible indicating tabs having hinged tongues fitted to be inserted in said 20 grooves, the grooves in the back face of the board being designed to hold the tabs not being used on the front face of the board.

In testimony that I claim the foregoing as my invention, I have signed my name 25 this 29th day of July, 1918.

WILLIAM W. WHITE.
